UNITED STATES PATENT OFFICE.

EDWARD A. TUTTLE, OF NEW YORK, N. Y., ASSIGNOR TO "THE TUTTLE AND BAILEY MANUFACTURING COMPANY," OF SAME PLACE.

DESIGN FOR A HOT-AIR REGISTER.

Specification forming part of Design No. 5,935, dated June 11, 1872.

Specification describing a new and original Design for Circular Register, invented by EDWARD A. TUTTLE, of the city, county, and State of New York.

The accompanying photograph fully represents my new invention.

This invention relates to a new design for a circular register for hot-air flues or other purposes. The design consists chiefly in the arrangement about a small circular center of four or more heart-shaped scrolls or figures, whose points reach the small center, while their sides intersect, and their outer parts

nearly reach the circular border of the register. Arabesques are interposed between the said border and the heart-shaped figures, and ornament the latter also directly, as shown, while within the point or inner part of each heart a small reticular ornament is placed.

I claim as my invention—
The design for a circular register, as shown.
EDWARD A. TUTTLE.
